ATTORNEY.

UNITED STATES PATENT OFFICE

HENRY SCHIERLOH, OF KANSAS CITY, MISSOURI

CONTROL MECHANISM FOR STEAM HEATING SYSTEMS

Application filed December 6, 1930. Serial No. 500,547.

This invention relates to automatic control for boilers or the like, and particularly to means for automatically regulating the fire in a furnace.

5. An object of the invention is to provide a control member which may be fitted to a standard furnace to automatically regulate feed of fuel to the fire.

A further object of the invention is to have
10 the device adjustable to fit various sizes and
types of furnaces.

These and other objects are accomplished by means of the following construction, in which:

15 Fig. 1 is a perspective view illustrating a preferred form of the invention.

Fig. 2 is a detail plan view showing the lower attaching member.

Referring to the drawing, 5 is a steam boiler on a furnace having a pipe 6 leading from the interior thereof to a diaphragm chamber 7. The chamber 7 contains a diaphragm adapted to receive steam pressure from the boiler on one face and has attached to and projecting from the opposite face a shaft 9 which carries at its upper end a rod 10, which is pivotally connected to the shaft 9 and to a support 11 on the diaphragm chamber 7. The rod 10 is provided with a weight 13 to partially balance steam pressure.

Attached to the top of the furnace is a frame which may be generally designated at 15, and comprises a horizontal angle iron 17 and a vertical angle iron 18. The lower angle 35 17 is connected to the furnace by means of a U-bolt 19 encircling the pipe 6 and which is adjustable in the slots 20. The vertical angle 18 carries a U-shaped frame member 22 adjustably mounted on the said angle 18 by 40 means of the bolts 23 and the slot 24.

means of the bolts 23 and the slot 24.

At the upper end of the U-member 22 there is rockingly connected a lever assembly or an operating frame designated 26. The frame 26 comprises a rod or bar 27 having one end thereof bent downwardly at right angles to the rod 27, as shown at 29. The rod 10 passes through the lower portion of the U-shaped member 22 and between adjustable pegs 30 mounted in the slot 32 of the bent down portion 29. A weight 34 is adjustably

mounted on the rod 27 to act as a counter-balance for the weight of the bent down portion 29.

Rigidly attached to the frame 26 and projecting upwardly at right angles thereto from the pivotal point is an actuating arm 36 which may have a rubber covered weight 37 at the upper end. The weight 37 is adapted to travel between the stop 39 and the stop 40 on the adjustable arm 41. The stops 39 and 40 are adjustably mounted on the arm 41 by means of slots or equivalent means. The said arm 41 is adjustably mounted on the vertical angle 18 by means of nuts 42 and slot 43. An electric switch 45 is attached to the angle 18 through an arm 46. The switch may be of the knife type as shown, or any other suitable type desired.

A link 48 of insulating material is made adjustable in length and is connected to the arm 36. The link 48 contains a slot 49 adapted to receive the pin 50 which is attached to the switch throwing arm 52. 70

The control switch 45 controls an electrically operated valve 47 for controlling the flow of gas or other fuel into the furnace. 75

In operation the weight 13 is adjusted on the rod 10 so that at a given pressure the rod 10 will rise, pressing against the upper pin 30 and moving the frame 26 about its pivotal point and throwing the actuating arm 36 over towards the pin 40. The pin 50 will slide in the slot 49 until the weight 37 passes the angle 18, at which time the end of the slot 49 engages the pin 50 and the weight 37 becomes active to exert force in the rod 48 and disconnect the switch, shutting off the supply of fuel to the furnace. 80 85

When the steam pressure again goes below the required amount, the rod 10 will lower, contacting with the lower pin 30, and pivot the frame in the opposite direction, throwing the arm 36 again towards the pin 39. 90

When the weight 37 has passed the angle 18, the pin 50 comes in contact with the opposite end of the slot and the said weight 37 acts to close the switch and again turn on the supply of fuel.

What is claimed as new and desired to secure by Letters Patent is:

1. In combination with a pressure-actuated diaphragm surrounded by a casing, and an electro-magnetically-actuated valve controlling flow of pressure to said casing, a rod pivotally connected to the diaphragm and to said casing, a frame, means for mounting the frame in adjustable relation to said casing, spaced stop members carried by the frame, a lever assembly pivotally mounted on the frame including a bar having spaced stop means adjacent one of its ends for engaging opposite edges of said rod, and having a weight adjustably mounted on its opposite end, an arm fixed to the bar intermediate its ends and engageable with the stop members on the frame, a switch for controlling the valve, and means for operably connecting said switch to the arm.
2. In combination with a pressure-actuated diaphragm surrounded by a casing, and an electro-magnetically-actuated valve controlling flow of pressure to said casing, a rod pivotally connected to the diaphragm and to said casing, a frame adjacent the casing, adjustably spaced stop members carried by the frame, a lever assembly pivotally mounted on the frame including a bar having adjustably spaced stop means adjacent one of its ends for engaging opposite sides of said rod and having a weight adjustably mounted on its opposite end, a lateral arm fixed to the bar intermediate its ends and engageable with the stop members on the frame, a switch for controlling the valve, and means for operably connecting the switch to said arm.
3. In combination with a pressure-actuated diaphragm surrounded by a casing, a rod pivotally connected adjacent one of its ends to the diaphragm and to said casing, a weight adjustably mounted on the rod adjacent its opposite end, a frame, means for mounting the frame in adjustable relation to said casing, spaced stop members carried by the frame, a lever assembly pivotally mounted on the frame including a bar having a lateral end provided with adjustably spaced stop means for engaging opposite sides of said rod, a weight adjustably mounted on the opposite end of the bar, a lateral arm fixed to the bar intermediate its ends and provided with a weight engageable with the stop members on the frame, a switch carried by the frame, and means for operably connecting the switch to said arm.

55 In testimony whereof I affix my signature.
HENRY SCHIERLOH.
